UNITED STATES PATENT OFFICE.

WILLIAM ALONZO VINSON, OF BALTIMORE, MARYLAND.

STRINGED INSTRUMENT.

1,387,567.

Specification of Letters Patent. Patented Aug. 16, 1921.

Application filed December 27, 1919. Serial No. 347,783.

To all whom it may concern:

Be it known that I, WILLIAM ALONZO VINSON, a citizen of the United States, and a resident of Baltimore, in the State of Maryland, have invented certain new and useful Improvements in Stringed Instruments, of which the following is a specification.

My invention is an improvement in stringed instruments, and has for its object 10 to provide an instrument of the character specified by means of which a large variety of sounds and of musical tones may be produced, and which may be operated in a variety of ways.

15 A further object of the invention is to produce an instrument wherein the tension of the string may be constantly varied to produce sliding tones, commonly known as jazz.

20 In the drawings:

Figure 1 is a front view of the device;

Fig. 2 is a top plan view;

Fig. 3 is an end view;

25 Fig. 4 is a vertical section through the diaphragm;

Fig. 5 is a section on the line 5—5 of Fig. 2;

Fig. 6 is a side view of a modified construction of instrument;

30 Fig. 7 is a vertical section of a modified form of diaphragm;

Fig. 8 is a bottom plan view of the sound box;

Fig. 9 is a side view of a portion of the 35 neck showing the fret string;

Fig. 10 is a sectional view showing the manner of attaching the eye.

In the present embodiment of the invention a sound box is provided, consisting, as 40 shown more particularly in Fig. 4, of a concave disk 1 having the diaphragm 2 connected with the edges of the disk, by bending the edges of the diaphragm over the edge of the disk as indicated at 3. The disk 1 has a central opening 4 and to the disk 45 at the opening is secured a tubular member 5, the said tubular member having a marginal flange 6 which fits against the face of the disk, about the opening, the disk being flattened for a slight distance beyond the opening, and a horseshoe shaped clamping member 7 is provided, the said clamping member being secured to the disk and engaging over the flange, to hold the tubular member 5 to the disk. The clamp 7 is secured to the disk, and the tubular member

may be engaged therewith by slipping the flange between the clamp and the disk, the inner portion of the clamp being spaced apart from the disk to permit this insertion. 60

An amplifier 8, in the form of a horn, is connected with the tubular member 5, the end of the horn fitting in the tubular member, and being held thereto in any suitable or desired manner, as, for instance, by the 65 clamp 9^a shown in Figs. 1 and 3. This clamp is in the form of similar sections which embrace the horn at the small end, and they are clamped on the horn by means of bolts and nuts 9. The clamp is supported in the 70 manner to be presently described. A washer 10 is secured to the center of the diaphragm on the opposite face from the disk, and this washer carries an eye 11, to which may be connected a flexible member 12, as, for instance, a string, to vibrate the diaphragm. 75

The air vibrations set up in the sound box by the vibration of the diaphragm are concentrated and amplified by the horn.

The instrument is operated to cause the 80 diaphragm to vibrate by means of the string, either by picking the string, bowing it or sliding it through the fingers. The string may be held with one hand and plucked with the other, or it may be drummed upon with 85 sticks, padded if desired. The pitch of the sound produced by the instrument is varied by varying the tension of the string.

In Figs. 1 and 2, that end of the string remote from the eye 11 winds upon a key 90 13 supported by a neck 16 connected to a post 17 which supports the sound box and amplifier in a manner to be presently described, and this neck has a handle or grip 15 at its outer end. A bridge 43 is provided 95 adjacent to the key 13, and between the same and the sound box over which the string passes. This post 17 is connected to a seat 19 by upper and lower bars 20 and 21.

The neck 16 is pivoted at 22 to the post 100 to swing on a vertical axis, and it will be evident that by swinging the neck laterally the string 12 may be relaxed or tightened, because the pivot pin 22 is lateral with respect to the string. The neck is also pivoted on a 105 horizontal axis 23, the neck being sectional, and the sections being connected by the pivotal connection 23. This pivotal connection is adjacent to the pivotal connection 22, and the arrangement permits the neck to swing 110 vertically or laterally. It will be evident that when the neck is swung downwardly,

or when it is swung laterally, the cord 12 will be tightened, and when the neck is returned to normal, straight position, the cord will be relaxed. Thus, by swinging the neck 5 either laterally or vertically, the tension of the cord may be varied to vary the pitch of the sound produced by the vibration thereof. The provision of two pivotal connections for the neck is merely a matter of convenience. 10 When the operator is seated in the seat 19, it will be more convenient to swing the neck laterally to vary the tension of the cord, while when the operator is standing, it will perhaps be more convenient to swing the 15 neck vertically. Openings 18^a are provided in the length of the neck in the upper face thereof, for receiving a pin 18, the pin acting as a fret against which the string may be pressed to shorten the effective length there- 20 of, to raise the pitch of the sound produced.

A drawer 24 is provided in the seat, for containing extra parts, strings or the like. It will be understood that the strings may be ordinary cord, waxed cord, catgut, wire 25 or any other suitable material. The diaphragm may be of any suitable material, and the string may be plucked or beaten to actuate the diaphragm to produce sound. In order to produce heavy bass notes the 30 string will be heavy, while to produce treble notes the string will be lighter.

In the embodiment of the invention shown in Fig. 6 the sound box 25, which corresponds to that shown in Figs. 1 and 2, and 35 which is connected to the amplifier 26 in the same manner as the sound box 1 and 2 is connected to the amplifier 8, has connected with the diaphragm thereof a string 27, provided at its free end with a ring 28, or other 40 form of grip. The string is connected to the diaphragm in the same manner as the string 12 is connected to the diaphragm 1-2, and instead of providing a permanent anchorage for the end of the string the anchorage is 45 provided by the hand of the operator engaging the grip 28. The operation is the same except that the player controls the tensioning of the string directly, and he may also shorten the string by grasping it at dif- 50 ferent points.

In the embodiment of the invention shown in Fig. 7 the sound box comprises a disk 29 and a diaphragm 30, the disk having a marginal flange 31 extending toward the convex 55 face, and the edge of the diaphragm 30 is clamped about this flange, somewhat similar to the mounting of a banjo head, by means of rings 32 and 33 which are secured together by screws 34, and to an outwardly ex- 60 tending marginal rib 31^a on the flange 31.

The edge of the diaphragm is held between the rings and between the ring 33 and the flange 31. The screws 34 are engaged by nuts 34^a on the under side of the rib 31^a, and 65 it will be evident that by means of the nuts,

which have radial openings for receiving a tool to turn the same, the tension of the head or diaphragm may be adjusted.

The tubular member or mouthpiece 35 is screwed into a nipple 36 which encircles the opening at the center of the disk, and a gasket 37 is arranged between the mouthpiece and the disk. The string is connected to an eye 38 at the center of the diaphragm, and this eye is connected to a reinforcing plate 39 on the opposite side of the diaphragm, the connection passing through the diaphragm. The simple form of device shown in Fig. 6 can be played in conjunction with the frame illustrated in Fig. 2, by holding 75 the horn 26 in the hand, engaging the rings with the frame, then drawing the string 27 taut or to the desired degree of tension, and for this purpose pegs 40 may be provided in the top of the post, or other suitable 80 places, for attaching or anchoring the strings of other jazzaphones of the simple type shown in Fig. 6, by placing the ring 28 over the pegs. Two or more of these pegs are provided for the purpose of attaching 90 two or more strings, since two or more strings may be anchored to the diaphragm of the same jazzaphone in eye 11, and, being anchored at two points a short distance apart, they may be played simultaneously 95 and two tones be "jazzed" at the same time. If desired, the eye 41 may be attached directly to the diaphragm 42 in the manner shown in Fig. 10.

The invention in its simplest form consists of the sound box comprising the diaphragm and a casing for inclosing a body of air at one face thereof, and having a suitable amplifier at the opposite side from the diaphragm, together with the string or 100 strings anchored to the diaphragm. A very great variety of sounds or musical tones may be produced upon the instrument and they may be produced in a variety of ways, the variation being accomplished by variations in the tension of the string or by varying the length of the string.

The device as a whole may be produced at a low price and is not difficult to learn to play. In practice, it has been found that 115 the opening in the sound box should be from one-sixth to one-fourth the diameter of the diaphragm, although it may be larger or smaller if desired.

When bowed with a violin bow, the instrument produces a tone similar to that of a violin, but by varying the thickness or length of the string or the tension a very great variety of effects may be obtained.

I claim:

1. An instrument comprising a sound box having one wall thereof formed by a flexible diaphragm and having an opening at the opposite wall, an amplifying horn detachably connected with the sound box at 120 130

- the opening and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the pivotal connection being lateral to the line of the string to vary the tension of the string when the neck is swung.
- 5 2. An instrument comprising a sound box having one wall thereof formed by a flexible diaphragm and having an opening at the opposite wall, an amplifying horn detachably connected with the sound box at the opening, and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the neck having a series of openings spaced longitudinally thereof and a peg adapted to engage one of the openings and the string for the purpose specified.
- 10 3. An instrument comprising a sound box having one wall thereof formed by a flexible diaphragm and having an opening at the opposite wall, an amplifying horn detachably connected with the sound box at the opening, and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the pivotal connection being lateral to the line of the string to vary the tension of the string when the neck is swung, said neck being also pivoted to swing at right angles to the plane of the diaphragm.
- 15 4. An instrument comprising a sound box having a flexible diaphragm and a cord connected with the diaphragm for vibrating the diaphragm when the cord is plucked or struck, a neck extending from the sound box, and having a key at the end remote from the sound box on which the cord is wound, said neck being pivoted to swing to vary the tension of the string.
5. An instrument comprising a sound box having a flexible diaphragm and a cord connected with the diaphragm for vibrating the diaphragm when the cord is plucked or struck, a neck extending from the sound box, said neck being pivoted to swing at its free end to vary the tension of the string.
- 20 6. An instrument of the character specified, comprising a sound box having a flexible diaphragm, and a cord connected with the diaphragm for vibrating the same when the cord is plucked or struck, means for supporting the end of the string remote from the sound box, and means for varying at will the tension of the string to vary the pitch of the note produced thereby.
- 25 7. An instrument of the character specified, comprising a sound box having a diaphragm and a cord connected with the diaphragm for vibrating the same when the cord is plucked or struck, and manually operating means for continuously varying the tension of the string for the purpose specified.
- 30 8. An instrument comprising a sound box having one wall thereof formed by a flexible diaphragm and having an opening at the opposite wall, an amplifying horn detachably connected with the sound box at the opening, and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the pivotal connection being lateral to the line of the string to vary the tension of the string when the neck is swung, said neck being also pivoted to swing at right angles to the plane of the diaphragm.
- 35 9. An instrument comprising a sound box having one wall thereof formed by a flexible diaphragm and having an opening at the opposite wall, an amplifying horn detachably connected with the sound box at the opening, and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the pivotal connection being lateral to the line of the string to vary the tension of the string when the neck is swung, said neck being also pivoted to swing at right angles to the plane of the diaphragm.
- 40 10. An instrument comprising a sound box having one wall thereof formed by a flexible diaphragm and having an opening at the opposite wall, an amplifying horn detachably connected with the sound box at the opening, and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the pivotal connection being lateral to the line of the string to vary the tension of the string when the neck is swung, said neck being also pivoted to swing at right angles to the plane of the diaphragm.
- 45 11. An instrument comprising a sound box having one wall thereof formed by a flexible diaphragm and having an opening at the opposite wall, an amplifying horn detachably connected with the sound box at the opening, and a cord connected with the diaphragm at the center thereof for vibrating said diaphragm when the cord is struck or plucked, a support for the sound box and amplifier, and a neck pivoted to the support and having a key at the end remote from the sound box upon which the end of the string is wound, said neck being pivoted to swing laterally parallel with the plane of the diaphragm, the pivotal connection being lateral to the line of the string to vary the tension of the string when the neck is swung, said neck being also pivoted to swing at right angles to the plane of the diaphragm.

WILLIAM ALONZO VINSON.
